UNITED STATES PATENT OFFICE

HARRY H. MCKEE, OF CHICAGO, ILLINOIS, ASSIGNOR TO SWIFT AND COMPANY, OF CHICAGO, ILLINOIS, A CORPORATION OF ILLINOIS

BRANDING DEVICE INK FEED

Application filed September 15, 1931. Serial No. 562,979.

The invention relates to marking apparatus, particularly adapted for applying an indication to a carcass, and provides an article which is easy of operation when in service.

5 The invention is directed to apparatus of the type embodying a rotary marker, a fount containing a marking fluid and a distributor for supplying the marking fluid to the marking elements.

10 The invention resides more particularly in the peculiar formation of the frame and the distributor which is detachably connected thereto. No claim is made herein to the method which constitutes the subject matter 15 of my copending application, Serial No. 415,838, filed December 21, 1929, for improvements in methods of marking meats.

For a full understanding of the invention and the merits thereof reference is to be had 20 to the drawings hereto attached and the subjoined description in which corresponding parts are designated in the several views of the drawings and referred to in the specification by like reference characters.

25 In the drawings:—

Fig. 1 is a side view of a marker illustrative of an embodiment of the invention.

Fig. 2 is a front view, the handle being omitted.

30 Fig. 3 is an enlarged fragmentary sectional view showing more clearly the fount and the distributor associated therewith.

Fig. 4 is an elevational view of the distributor and fastening means associated 35 therewith.

Fig. 5 is a side view of the parts illustrated in Fig. 4.

Fig. 6 is a rear view of the frame and rotary marker.

40 Fig. 7 is a plan view of one marking element.

Fig. 8 is a front view of a marking element.

The device includes a frame 1, handle 2, rotary marker 3 and distributor 4, the latter 45 being detachably connected to the frame. In the present instance the frame 1 is formed with a socket 5 in which the handle 2 is secured. A fork 6 receives the rotary marker 3 and as shown constitutes an integral part 50 of the frame. A tubular extension 7 projects

laterally from the frame 1 and constitutes the fount 4 containing the marking fluid. The chamber 8 for holding the marking fluid is formed in the lateral extension 7 and partly within the frame 1 and is closed at its outer end by means of a plate 9 in which is formed an opening 10 which constitutes an outlet for the fluid. An opening is formed in a side of the frame and communicates with the chamber 8 and is normally closed by means of a 60 plug 11 which is threaded therein. The marking fluid is supplied to the fount or chamber 8 through the opening which the plug 11 closes. The outer end of the tubular extension 7 is deflected downwardly at an obtuse angle and is recessed to receive a reduced portion 12 of the distributor 4, a packing 13 being disposed within the recess to insure a close fit between the distributor and fount. A lug 14 projects upwardly from the lateral extension 7 adjacent the outwardly and downwardly deflected end thereof and constitutes an abutment for a cam lever 15.

65 The distributor 4 constitutes a head to which is fitted a brush 16. A chamber 17 formed in the head 4 receives the brush 16. A small passage 18 leads from the chamber 17 and registers with the outlet 10 to receive fluid from the fount and conduct the same to the brush. A flange 19 projects outwardly from the part 4 adjacent the reduced end 12 which is adapted to overlap the end of the tubular extension 7. A bail 20 is fitted to opposite sides of the part 4 and the cam lever 15 is mounted thereon. When the distributor is placed in position it is held in place by means of the bail 20 and lever 15, the latter having its cam end abutting the lug 14. The lever 15 may be manipulated to draw the part 4 close against the recessed outer 70 end of the tubular extension 7 so as to obtain a close joint to prevent leakage.

75 The rotary marker consists of a wheel which is closed at its sides by means of plates 21. This wheel is mounted upon a spindle 22 which is supported in the members of the fork 6. Marking elements are applied to the outer surface or periphery of the wheel and consist of plates 23 and needles or like elements fitted thereto. The plates 23 are 80 85 90 95 100

detachably connected to the wheel to admit of ready removal for any desired purpose. The needles 24 are arranged in accordance with the design mark or other matter constituting the indication to be applied to the carcass or other article to be branded.

- 5 The fount 8 is adapted to be supplied with the marking fluid through the opening which is normally closed by means of the plug 11.
- 10 When the device is held in upright position the marking fluid passes from the fount through the opening 10 and passage 18 to the chamber 17 and is applied to the marker by means of the brush 16, as will be readily
- 15 understood. In practice the device is run down the side of the carcass with the brush 16 directed toward the carcass. This results in the needles 24 nearest the brush 16 penetrating the carcass and insures an easier operation than if the apparatus were manipulated with the brush 16 facing the operator.
- 20

What is claimed is:

1. A marker comprising a frame having an offset extension in which is formed a chamber constituting a fount to contain marking fluid, said chamber having an outlet and a recess in line with the outlet, and a distributor having a reduced portion snugly fitting the said recess and detachably connected to the offset extension.
- 25
2. A marker comprising a frame having a chambered offset extension from which a lug projects, a distributor detachably fitted to said extension, a bail applied to the distributor and a lever mounted upon the bail and engageable with the lug to hold the distributor when placed in position.
- 30
3. A marker comprising a frame having a handle and provided with a fork, a rotary marker mounted in said fork, a fount projecting laterally from the frame, a distributor detachably fitted to the fount, a bail applied to the distributor and a lever mounted upon the bail and engageable with the fount to hold the distributor when placed in position.
- 35
4. A marking device of the character specified comprising a frame having a tubular extension projecting laterally therefrom with its outer end deflected downwardly, said extension having an offstanding lug and having the chamber formed therein extending partly into the frame, a distributor detachably fitted to the deflected end of the lateral tubular extension, a bail carried by the distributor and a lever mounted upon the bail and engageable with the said lug.
- 40
5. A marker comprising a frame including a socket and fork and having a lateral tubular extension with its outer end deflected downwardly and provided with an offstanding lug, said frame having a portion chambered to register with the chamber of the lateral extension and provided with a filling opening, a plug closing the filling opening, a distributor having a reduced end fitted to
- 45
- 60
- 65

the deflected end of the lateral extension, a bail applied to the distributor, a lever mounted upon the bail and engageable with the said lug and a rotary marker mounted in the fork of the frame.

Signed at Chicago, in the county of Cook and State of Illinois, this 14th day of September, 1931. 70

HARRY H. MCKEE.
